UNITED STATES PATENT OFFICE.

GEORGE S. WHEAT, OF NEW YORK, N. Y.

DESIGN FOR A BUTTON OR EMBLEM.

53,326.

Specification for Design.

Patented May 13, 1919.

Application filed December 14, 1918. Serial No. 266,824. Term of patent 3½ years.

To all whom it may concern:

Be it known that I, GEORGE S. WHEAT, a citizen of the United States, residing in the borough of Manhattan, in the county, city, and State of New York, have invented a new, original, and ornamental Design for a Button or Emblem, of which the following is a specification, reference being had to the accompanying drawing, forming part thereof.

The figure is a plan view of a button showing my new design.

I claim:

The ornamental design for a button or emblem, as shown.

GEORGE S. WHEAT.
